Inventor

CHARLES WAGNER

By his Attorney

Julius H. Fink

UNITED STATES PATENT OFFICE.

CHARLES WAGNER, OF GRANTWOOD, NEW JERSEY.

PRINTING PLATE AND METHOD OF PRODUCING THE SAME.

Application filed June 25, 1921. Serial No. 430,288.

To all whom it may concern:

Be it known that I, CHARLES WAGNER, a citizen of the United States, and a resident of Grantwood, in the county of Bergen and State of New Jersey, have invented certain new and useful Improvements in Printing Plates and Methods of Producing the Same, of which the following is a specification.

This invention relates to improvements in printing plates and methods of producing the same.

One of the objects of this invention is to produce a printing plate comprising a sheet of relatively thin impressible material, such as sheet zinc, copper, aluminum, etc., provided with a printing surface formed of impressions of suitable subject-matter impressed through the plate from the obverse to the reverse side thereof so as to cause such impressions to be raised or embossed on said reverse side. Such impressions are preferably coated with carbon or other suitable material, and to this end, the plate is preferably backed with a sheet of carbon paper or the like disposed with the carbon-covered face of the paper abutting against the reverse side of the metallic sheet so that the impressions or impressed portions of the plate will take up and become coated with such material inert to the action of an etching bath, the uncovered portions of the plate being etched or treated with chromic acid to cause the same, when wetted with water, to be ink-rejecting.

Another object of my invention is to provide an extremely simple process for producing a durable printing plate which may be used effectively to make a large number of printed copies without destruction and, to this end, I take a sheet of suitable hard and impressible material, and preferably a sheet of metal such as zinc, copper, aluminum, etc., and back up the same with a sheet of carbon paper having the carbon-covered face thereof disposed toward and abutting against the reverse side of the metallic plate. I then, either by the use of a sharp instrument, typewriter or other suitable means, impress through the relatively thin printing plate or shell the particular subject-matter which it is desired to print. Upon such impression, the carbon of the carbon paper will adhere to and coat or cover the impressed, raised portions of the plate only, leaving the balance of the reverse surface free. The surface of the plate having these

raised or impressed and coated portions is now preferably treated to cause the unraised and uncovered portions to be ink-rejecting or otherwise treated in any conventional manner, for example, by the use of a suitable chromic acid solution or its equivalent, such as is usual in lithographing or like arts, and such reverse side is thereafter inked and printed from in any known manner. A plate so produced provides a printing surface with sharp raised outlines of the impressed and coated characters on the reverse side of the plate and a large number of prints may be made from such plate.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:

Fig. 1 is a plan view of a metallic printing plate backed up by a sheet of carbon paper and having printed characters impressed through the metal plate;

Fig. 2 shows a metal plate and carbon in a typewriting machine having the characters simultaneously impressed through the metal and coated with carbon; and

Fig. 3 is a section through a portion of a printing plate made in accordance with my invention.

Referring now to these drawings, 1 indicates a plate of suitable material which is preferably composed of thin sheet metal such as zinc, copper, aluminum or the like, and 2 indicates a sheet containing a surface of carbon or other suitable character-covering substance. When a sheet of carbon is used, it is placed with its carbon face abutting against the reverse side of the printing plate. The subject-matter to be printed is then impressed through the plate by impressions on the obverse side so as to cause pressure through the impressible material and adherence of the carbon or like material on the raised or impressed portions of the reverse side.

The impression of the characters or subject-matter to be printed may be impressed from the obverse to the reverse side in any suitable manner, as, for example, a printing plate of any type or other design may

- be employed and impressed into and through said plate by a suitable press or in any other way, or in accordance with my preferred method, the metallic plate which is thin and flexible may, with its backing of carbon or like covering material, be inserted in a type-writing machine and the impressions from the type of such a machine may be made through such metal plate by striking the 10 type on the obverse side in the usual manner of typewriting except that no ribbon is employed. This will cause the usual reverse type similar to that on the typewriting machine to be formed on the reverse side of the 15 metal sheet and these reverse type or characters will be covered by carbon or like covering material.

In plates of this character, however, the 20 signature of a person may be readily impressed in the plate by a pencil or other sharp instrument and when so impressed a reversed reproduction thereof in relief and coated with carbon will be formed on the reverse side thereof. Similarly copies of 25 electrotypes or other printing surfaces may be made by simply impressing such printing surfaces into the obverse side of my hard impressible printing plate so as to procure carbon coated raised surfaces on the opposite side thereof. The surface of the plate 30 having these raised or impressed and coated portions is now preferably treated with a suitable chromic acid solution to cause the unraised and uncovered portions when 35 wetted with water to be ink-rejecting or said plate may be otherwise treated in any conventional manner such as is usual in lithographing or like arts, and such reverse side is thereafter inked and printed from in any 40 known manner. A plate so produced provides a printing surface with sharp raised outlines of the impressed and coated characters on the reverse side of the plate and a 45 large number of prints may be made from such plate.

Having described my invention, I claim:

1. A printing surface comprising a sheet of suitable material having reversed printing matter impressed through the plate and raised on the reverse side thereof, said raised surface having a coating of a suitable covering substance and the unraised and uncovered portions of said plate having an ink-rejecting surface.
2. A printing plate comprising a sheet of metal having reversed printing matter im-

pressed through the plate and raised on the reverse side thereof, said raised surface having a coating of carbon, and the unraised and uncovered portions of said plate having an ink-rejecting surface.

3. The process of producing printed plates comprising the taking of a relatively thin sheet of suitable hard though impressible material, impressing therein suitable subject-matter to be printed, covering the raised surface with a suitable covering material, treating the uncovered portion of such plate to cause the same to be ink-rejecting, and then utilizing said plate as a printing surface.

4. The process of producing metal plates comprising the taking of a relatively thin sheet of suitable hard though impressible material, impressing therein suitable subject-matter to be printed, covering the raised surface with carbon, treating the uncovered portion of such plate to cause the same to be ink-rejecting and then utilizing the said plate as a printing surface.

5. The process of producing printed plates comprising the taking of a relatively thin sheet of suitable hard though impressible material, superimposing said thin impressible sheet on another sheet carrying a covering substance adapted to adhere under pressure and impressing through said hard impressible plate suitable subject-matter for printing, whereby the impressed subject-matter is coated with said material, and treating the uncoated portions of said plate.

6. The process of producing metal plates comprising the taking of a relatively thin sheet of suitable hard though impressible material, backing up such metal plate with a sheet of carbon paper with the carbon surface abutting against the reverse side of the metal plate, impressing printing characters through said plate to simultaneously procure the raising of reverse characters and the covering thereof with carbon, then treating the unraised and uncovered portions to cause the same to be ink-rejecting and then utilizing said plate as a printing surface.

In witness whereof, I have signed my name to the foregoing specification in the presence of two subscribing witnesses.

CHARLES WAGNER.
